CLAIM

The ornamental design for a magnetic resonance imaging device as shown and described.

DESCRIPTION

FIG. 1 is a front elevational view of a magnetic resonance imaging device in accordance with our design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a perspective view thereof.

The evenly-spaced broken lines represent portions of the magnetic resonance imaging device which form no part of the claimed design. The dot-dash boundary line encloses a portion of the magnetic resonance imaging device which forms no part of the claimed design.

1 Claim, 7 Drawing Sheets
